BOOK HOLDER AND LINE FINDER

Paul A. Jones, San Francisco, Calif.

Application November 21, 1933, Serial No. 699,073

2 Claims. (Cl. 120—34)

This invention relates to new and useful improvements in book holders and line finders, and has for its principal object to provide a device of this character which will facilitate the preparation of typewritten or other copies from the text of law books or other material.

A further object of my invention is to provide novel and efficient manually operated means for intermittently actuating and lowering the line finder and associated parts, as required in the preparation of the typewritten or other copy.

A still further object of my invention is to provide novel means for varying the amount or degree of the intermittent movement of the line finder, to correspond with the different size type of the law books or other material from which the copy is made.

Still another object of my invention is to provide a novel support for the book and simple but effective means for holding the book and pages in proper position for "copying" on said support.

With the foregoing and other objects in view that will appear as the nature of my invention is better understood, the same consists in the novel features of construction, combination and arrangement of parts illustrated in the accompanying drawings and more particularly pointed out in the appended claims.

In the accompanying drawings, which are for illustrative purposes only and are therefore not drawn to scale:

Figure 1 is a front elevation of a book holder and line finder, embodying my improvements.

Figure 2 is an edge view.

Figure 3 is a vertical transverse section, taken on line 3—3 of Figure 2, with the parts represented on an enlarged scale.

Figure 4 is a similar view, taken on line 4—4 of Figure 3.

Figure 5 is a horizontal section, taken on line 5—5 of Figure 1, with the parts shown on an enlarged scale.

Figure 6 is a vertical transverse section, taken on line 6—6 of Figure 1.

Figure 7 is a similar view, taken on line 7—7 of Figure 3.

Figure 8 is also a vertical transverse section, taken on line 8—8 of Figure 6.

Figure 9 is a horizontal section, taken on line 9—9 of Figure 6 and Figure 10 is a horizontal section, taken on line 10—10 of Figure 2.

Referring to the drawings for a more particular description of my invention, and in which drawings like parts are designated by like reference characters throughout the several views, A

designates the book holder and B the line finder. As shown, the book holder comprises the lower rectangular oblong casing 1 and the upper adjustable back or panel 2. The top or ledge 3 of the casing 1 forms a rest or support for the bottom of the book, and the adjustable panel 2, a support for the back of the book. The panel 2 may be held in adjusted position by the spring pressed ball bearings 4, or other equivalent means, and the top of the panel is provided with a hinged book holder 5, preferably in the form of a horizontal wire clamp equipped with a plurality of rubber buttons or rollers 6. The book holder 5 is adapted to swing in the arc of a circle and is normally held in book engaging position by the coil tension springs 7.

The line finder B is carried by the upper end of the vertical rack 8, whose lower end 9 works in the tubular guide 10, situated at the front center of the casing 1. The lower end 9 of the vertical rack may be provided with a spring pressed ball bearing 11, working in a vertical groove or ball race 12, formed in said tubular guide.

In carrying out my invention, the upper end of the vertical rack 8, extends through the upper and lower longitudinally disposed co-incident slots 13 and 14, formed in the hollow transversely disposed casing 15, and the line finder B is swiveled, as at 16, to the inner end of the casing, and held against the book pages by the coil spring 17 disposed in the casing between the inner end 18 of the latter and the inner edge, as 19, of the rack 8, in conjunction with the flat bowed spring 20 carried by a square stud 21, formed on said end 18 of the casing, with its opposite ends, 22, engaging the outer face of the line holder. A knurled nut 23 is screwed on the outer threaded end 24 of the casing 15, and this nut is provided with an inwardly tapering plug 25, which extends into the outer end of the casing, and prevents any bending in or distortion of the sides of the casing when the nut is screwed up.

A gear wheel 26 is arranged to engage the teeth 27 of the vertical rack 8, and this gear wheel is carried by one end of a horizontal shaft 28, journaled in suitable bearings 29 mounted on the inner face of the front wall 30 of the casing 1. The outer end of the shaft 28 is provided with a bevel pinion 31, which co-acts with a corresponding bevel pinion 32, carried by the upper end of the vertical shaft 33, journaled in the upper and lower horizontal arms or brackets 34 and 35, respectively, of the standard 36. The lower end 37 of the standard 36 is suitably fastened to the supporting base 38, which may be provided with rub-

ber suction feet 39, if desired. The lower end of the shaft 33 is also provided with a bevel pinion 40, which intermeshes with a corresponding beveled pinion 41, carried by the outer end of the 5 horizontal driven shaft 42. The outer end of the driven shaft is also provided with a ratchet wheel 43, normally engaged by a spring controlled pawl 44, carried by one face of the disc wheel 45, keyed to the inner section 46 of the drive shaft. The 10 outer section, as 47, of the drive shaft, is journaled in suitable bearings 48 and 49, formed at the top or upper edge of the shaft support 50. The inner and outer sections of the drive shaft are provided with a suitable clutch or union 51 and the outer end of the outer section with an 15 actuating arm or lever 52. It will be noted that the inner end of the drive shaft support is provided with a housing 53, which fits over a corresponding ledge or extension 54, extending outwardly from the adjacent lower corner of the front wall 30 of the casing 1. The housing may be secured in removable position by the screw 55 and the outer end of the support 50 may be provided with a rubber suction cup 56.

20 25 30 35 40

An adjustable segment 57, is loosely connected to the outer end of the driven shaft 42 and is provided at its outer edge with a cam 58 disposed in the path of movement of the nose 59 of the pawl 44. The segment 57 is provided with a transverse pin 60, which extends through an arcuate slot 61 formed in the front wall 30 of the casing 1 and is provided at its outer end with a knob and pointer 62.

In practice, the line finder is intermittently actuated and lowered by pressing on the arm or lever 52, which turns the drive shaft one-quarter of a revolution to the right and through the medium of the ratchet and gear connections described, causes the gear wheel 26 to lower the vertical rack 8 accordingly. To vary the amount or degree of the intermittent movement of the

rack and line finder to accommodate the device to different size type, the segment 57 is adjusted by the knob and pointer accordingly, with the result that when the drive shaft 42 has been turned a pre-determined distance, the pawl 44 will be disengaged from the ratchet 43 by the cam 58 and the remainder of the quarter turn of the disc wheel 45 completed, with the pawl idle.

From the foregoing description taken in connection with the drawings, it is thought that the construction, operation and advantages of my invention will be readily understood without requiring a more extended explanation.

Various changes in the form, proportions and minor details of construction may be resorted to without departing from the principles or sacrificing any of the advantages of my invention, as defined in the appended claims.

Having described my invention, what I claim as new and desire to secure by Letters Patent, is:

1. In a device of the character specified, a book support, a vertical rack, a supporting sleeve adjustably mounted on the upper end of the rack, a line finder carried by the supporting sleeve, an actuating lever and a ratchet and gear mechanism for intermittently lowering the rack and line finder when said lever is actuated.

2. In a device of the character specified, a book support, a vertical rack, a supporting sleeve adjustably mounted on the upper end of the rack, a line finder carried by the supporting sleeve, an actuating lever, a ratchet and gear mechanism for intermittently lowering the rack and line finder when said lever is actuated and adjustable means for varying the amount or degree of intermittent movement of the rack and line finder when said lever is actuated, to correspond with different size type.

PAUL A. JONES.
